UNITED STATES PATENT OFFICE.

HERBERT T. HERR, OF DENVER, COLORADO.

COMBINED ENGINE AND COMPRESSOR.

1,161,128.

Specification of Letters Patent. Patented Nov. 23, 1915.

Original application filed May 14, 1908, Serial No. 432,881. Divided and this application filed October 12, 1908. Serial No. 457,231.

To all whom it may concern:

Be it known that I, HERBERT T. HERR, a citizen of the United States, residing at Denver, in the county of Denver and State 5 of Colorado, have invented new and useful Improvements in Combined Engines and Compressors, of which the following is a specification.

This invention relates to internal combustion engines and more particularly to that 10 type covered by my prior pending application, Serial No. 432,881, filed May 14, 1908, and of which this application is a division.

One of the objects of this present invention 15 is to provide improved means for compressing air for use in scavenging the cylinders of the engine.

Another object is to effect a more thorough 20 clearing out of the products of combustion from the cylinders. And still another object is to provide a combined engine and compressor construction in which the air to be used for fuel injecting, starting, and for other purposes may be compressed by 25 means of the engine pistons without the necessity of additional moving parts.

In the accompanying drawings, Figure 1 is a vertical longitudinal section of a three-cylinder engine embodying my improvements; Fig. 2 a transverse section taken 30 through one of the engine cylinders; and Fig. 3 a horizontal section of one of the engine cylinders taken substantially on the line $x-x$ of Fig. 2.

The invention is illustrated as comprising 35 a plurality of cylinders, in the present instance, three. These cylinders are designated by the reference numeral 4 and are supported upon suitable crank cases which may 40 be separate castings or which may be formed in a single casting. The shaft 5 is journaled in suitable bearings in the crank case. The shaft receives its motion from the pistons 1 connected to said shaft by the piston rods 6. 45 Each cylinder 4 is provided with exhaust ports 2 which exhaust through outlets 3. By reference to Fig. 2 it will be observed that the piston 1 in each cylinder is larger in diameter at one end than at the other. The 50 larger end of the piston is adapted to compress air in the crank case by drawing the air through a port normally closed by the valve 107 on the compression stroke of the piston and force air through a port normally

closed by the valve 108 upon the power 55 stroke of the piston. The air passed through the port closed by the valve 108 will enter the chamber 109 through the port 110, said port 110 communicating with a valve chamber 111 normally closed by valve 112 60 so that when the exhaust ports 2 are uncovered the pressure on one side of the valve 112 will be atmospheric pressure and the compressed air may enter the cylinder 4 to scavenge it. This invention also contemplates utilizing the piston within the cylinder for compressing air to be subsequently used for certain purposes, as for example, for initially starting the motor. On the first cylinder is an air strainer 95 adapted to permit air to enter a chamber 96 and by unseating a check valve 97 pass into the clearance spaces 98 and then to a cylinder 99. In the first cylinder is a discharge valve 100 permitting communication with a cavity 75 101 which in turn communicates with a port 102 leading to an intercooler 103. Ports 113 and 114 from the second cylinder communicate with the intercooler and these ports communicate with a chamber 116 through the 80 chamber 104, the chamber 114 being provided with valves corresponding to valves 97 and 100. The chamber 116 also communicates with an intercooler 105 through the port 117. The third cylinder is provided 85 with ports 118 and 119 leading into the head 120 through the chamber 106, the chamber 119 being provided with valves corresponding to valves 97 and 100. The head 120 is provided with a passage 121 90 communicating with a high pressure reservoir A. It is to be understood that the cylinders 99, 104 and 106 are of decreasing capacity to provide for series compression.

In Fig. 3 I have shown a sectional view on 95 the line X X of Fig. 2. This sectional view is taken through the first cylinder and shows the strainer 95. Views taken through the remaining cylinders on the line X X would show the same construction as Fig. 2 except 100 that instead of the strainer 95 the cylinder would be connected to the preceding one at this point.

The operation of the compressor is as follows: On the descent of piston 1, which gives 105 the low pressure cycle, air is taken through air strainer 95 to chamber 96, unseating check valve 97, into clearance space 98, and

from thence into cylinder 99. Atmospheric pressure therefore obtains in space 99 as shown. On the upward stroke of the piston, this air is compressed in space 99 until it reaches sufficient pressure to unseat discharge valve 100, when it flows into cavity 101, and from there through port 102 into intercooler 103. This gives compression from atmospheric pressure, to say 100 pounds per square inch per revolution of the engine. Air is taken from intercooler 103 through similar ports 113 into chamber 114 in intermediate head 115 on the second engine, passing a suitable admission valve 10 similar to that previously described in the first stage as taken into the space 104, and on the upward stroke of the piston is compressed until its pressure is sufficient to unseat a discharge valve similar to that previously described in the first stage, discharging its air through chamber 116 and port 117 into intercooler 105; from intercooler 105 air is taken at the pressure of say 300 pounds per square inch, in the same manner as previously described in the other engines, through ports 118 and 119 in intermediate head 120 into the space 106 in the third engine on the downward stroke of the piston, and on the upward stroke this air is compressed to say 800 pounds per square inch, being finally discharged through a suitable discharge valve into chamber 121 and the high pressure reservoir A. It will also be seen that on the upward stroke of each piston the displacement of the piston causes air to unseat receiving valves into the crank case as shown in Fig. 2 at 107. On the downward stroke of the piston these admission valves close, and discharge valves 108 open, and by suitable port in the casting discharge the compression of the downward stroke into chamber 109 or into chamber 111 where the pressure of chamber 109 is always present above valve 112 in the cylinder heads. The downward stroke of the piston compressing air into 109 will cause the opening of valve 112 when exhaust ports 2 are opened by piston 1 allowing the compressed air from chamber 109 to flow through the cylinder and drive the burnt gases through the exhaust port, filling cylinder 4 with pure air on the completion of each down stroke, which is compressed on the up stroke

to the ignition compression previously described. 55

Having now described my invention, what I claim as new and desire to secure by Letters Patent is:

1. In a combined internal combustion engine and multi-stage compressor, the combination of a multiple number of cylinders formed to accommodate differential pistons, a differential piston mounted in each cylinder and dividing the cylinder into a combustion chamber, located at one end thereof, and an annular compression chamber, valve means for controlling communication between the annular compression chambers of the cylinders, whereby the annular chambers of all the cylinders coöperate to form a multi-stage compressor, a crank shaft common to all of said pistons, a multi-chamber crank case inclosing said shaft and into which air is drawn and compressed by the operation of at least one of said pistons, and a valve between said case and the combustion chambers of each cylinder for delivering air to the combustion chambers of the cylinders. 60 65 70 75

2. In a combined internal combustion engine and multi-stage compressor, the combination of a plurality of cylinders open at one end and formed to accommodate differential pistons, a differential piston located in each cylinder and dividing the cylinder into a combustion chamber located at one end thereof and an annular compression chamber, valve means for controlling communication between the annular compression chambers of the cylinders whereby they coöperate to form a multi-stage compressor, a crank shaft, common to all of said pistons, a crank case inclosing said shaft and communicating with the open ends of said cylinders and into which air is drawn and compressed by the operation of at least one of said pistons and valve means for controlling the delivery of air to and the discharge of air from said crank case. 80 85 90 95

In testimony whereof I have hereunto set 100 by hand.

HERBERT T. HERR.
